(57) **CLAIM**

The ornamental design for a microphone stand, as shown and described.

DESCRIPTION

FIG. 1 is a front-side perspective view of a microphone stand;

FIG. 2 is a rear-side perspective view of the microphone stand;

FIG. 3 is a front elevational view of the microphone stand;

FIG. 4 is a rear elevational view of the microphone stand;

FIG. 5 is a top plan view of the microphone stand;

FIG. 6 is a bottom plan view of the microphone stand;

FIG. 7 is a right-side elevational view of the microphone stand;

FIG. 8 is a left-side elevational view of the microphone stand;

FIG. 9 is a sectional view of the microphone stand taken in the direction of line 9-9 of FIG. 3; and,

FIG. 10 is a perspective view of the microphone stand shown in an environment of use.

Portions of the microphone stand shown in evenly-spaced broken lines form no part of the claimed design. The dot-dot-dash line showing of a microphone and a microphone pop filter attached to the microphone stand in FIG. 10 illustrates environmental structure and forms no part of the claimed design.
